UNITED STATES PATENT OFFICE.

HENRY MUENCH, OF BROOKLYN, NEW YORK.

FILTERING-BAG.

SPECIFICATION forming part of Letters Patent No. 272,576, dated February 20, 1883.

Application filed June 26, 1882. (No model.)

To all whom it may concern:

Be it known that I, HENRY MUENCH, of Brooklyn, in the county of Kings and State of New York, have invented certain new and useful Improvements in Filtering-Bags, of which the following is a specification.

In the filtering of saccharine liquors woven bags of twilled fabric were heretofore employed which were suspended and surrounded by cylindrical sleeves of coarser material and of considerably less diameter, so as to form in the bags a number of folds and thereby a large filtering-surface in a small space. These filtering-bags are employed to retain the scum and other gummy impurities contained in the saccharine liquor, but require to be frequently removed and washed so as to clean them from the impurities deposited on their surface. The twilled filtering-bags heretofore used had the disadvantage that the surface was of a too uniform character, so as not to offer a sufficient resistance to the passage of the liquor, so that the scum was mainly collected at the lower part of the bag, whereby the filtering operation did not take place uniformly over the whole bag. This necessitated the frequent removal and washing of the bags, by which they were soon worn out, became less and less adapted for filtering, and caused a considerable loss of time and labor in their frequent changing.

The object of my invention is to furnish for sugar-refineries and other establishments in which filtering operations are carried on an improved filtering-bag by which a more uniform and regular filtering action is obtained; and the invention consists of a filtering-bag made of a fabric woven at both sides with raised intercrossing ribs, so that cellular spaces or indentations are formed between the ribs, within which the scum is deposited in an effective and uniform manner over the entire surface of the bags.

In the accompanying drawings, Figure 1 represents a side view of my improved filtering-

bag; and Figs. 2 and 3, a side view and vertical transverse section of a portion of the fabric from which my bag is made, drawn nearly in natural size.

Similar letters of reference indicate corresponding parts.

In the drawings, A represents my improved filtering-bag, which is closed in the customary manner at the bottom and hemmed at the upper edge. It is woven on power-loom in the manner well known to every practical weaver, with extra warp and filling threads at each side, which threads are bound off in such a manner that rectangularly-intercrossing ribs *a a* are formed both sides of the web, and that between the ribs cellular depressions or indentations *b b* are obtained. The effect of the intercrossing ribs and cellular depressions is that a considerably larger filtering-surface is obtained which impedes the passage of the saccharine liquor through the bag, and which serves to retain the scum and other impurities in a more effective manner. The result will be that a more uniform filtering action takes place over the entire surface of the bag, that bags made of such fabric can be used much longer without being changed, that they require to be less frequently washed, and that they are more durable and consequently less expensive.

Having thus described my invention, I claim as new and desire to secure by Letters Patent—

A filtering bag made of a woven fabric provided with intercrossing ribs and with cellular depressions or indentations between the ribs, substantially as and for the purpose set forth.

In testimony that I claim the foregoing as my invention I have signed my name in presence of two subscribing witnesses.

HENRY MUENCH.
